US00D982527S

(12) **United States Design Patent** (10) **Patent No.:** **US D982,527 S**
Li et al. (45) **Date of Patent:** **** Apr. 4, 2023**

(54) **ELECTRIC CONNECTOR**

(71) Applicant: **LUXSHARE PRECISION INDUSTRY CO., LTD.**, Shenzhen (CN)

(72) Inventors: **Huabing Li**, Shenzhen (CN); **Zhongyuan Lai**, Shenzhen (CN); **Chenhai Zeng**, Shenzhen (CN); **Yu Huang**, Shenzhen (CN)

(73) Assignee: **LUXSHARE PRECISION INDUSTRY CO., LTD.**, Shenzhen (CN)

(**) Term: **15 Years**

(21) Appl. No.: **29/776,430**

(22) Filed: **Mar. 30, 2021**

(30) **Foreign Application Priority Data**

Oct. 19, 2020 (CN) 202030621801.6

(57) **CLAIM**

The ornamental design for an electrical connector, as shown and described.

DESCRIPTION

FIG. 1 is a front, top and right side perspective view of an electric connector showing our new design; FIG. 2 is a rear, top and left side perspective view of an electric connector showing our new design.

FIG. 3 is a front elevational view of the electric connector;

FIG. 4 is a rear elevational view of the electric connector;

FIG. 5 is a top plan view of the electric connector;

FIG. 6 is a bottom plan view of the electric connector;

FIG. 7 is a left side elevational view of the electric connector; and,

FIG. 8 is a right side elevational view of the electric connector.

The broken lines in the drawings illustrate portions of the electrical connector that form no part of the claimed design.

1 Claim, 8 Drawing Sheets
